(No Model.)

E. VERSTRAETE.
POLE FOR ELECTRIC WIRES, &c.

No. 435,872.

Patented Sept. 2, 1890.

Fig. I.

UNITED STATES PATENT OFFICE.

EDMOND VERSTRAETE, OF ST. LOUIS, MISSOURI, ASSIGNOR OF ONE-HALF TO
PETER M. KLING AND GEORGE J. KOBUSCH, OF SAME PLACE.

POLE FOR ELECTRIC WIRES, &c.

SPECIFICATION forming part of Letters Patent No. 435,872, dated September 2, 1890.

Application filed December 27, 1889. Serial No. 335,127. (No model.)

To all whom it may concern:

Be it known that I, EDMOND VERSTRAETE, of the city of St. Louis, in the State of Missouri, have invented a certain new and useful Improvement in Poles for Electric Wires, &c., of which the following is a full, clear, and exact description, reference being had to the accompanying drawings, forming part of this specification.

10 My invention relates to certain improvements in poles for electric wires, &c.; and my invention consists in features of novelty hereinafter fully described, and pointed out in the claims.

15 Figure I is a side elevation of my improved pole. Fig. II is an edge view of same or an elevation looking at the flanged side of the post. Fig. III is an enlarged section taken on line III III, Fig. I. Fig. IV is an enlarged vertical section taken on line IV IV, Fig. II. Fig. V is a transverse section taken on line V V, Fig. IV. Fig. VI is a transverse section taken on line VI VI, Fig. IV. Fig. VII is a detail elevation. Fig. VIII is a transverse section taken on line VIII VIII, Fig. IV. Fig. IX is a transverse section taken on line IX IX, Fig. IV; and Fig. X is a modification.

20 Referring to the drawings, 1 represents a pole made in halves 2 3, (see Fig. III,) each half having a flange 4 on each side, by which the halves are secured together through means of bolts or rivets 5.

25 6 represents a strip or diaphragm extending across the post and held between the flanges 4 by the rivets 5. This diaphragm extends vertically from the bottom of the post upwardly to a point indicated at 7, Figs. I, II, and IV. The object of this diaphragm is 30 to strengthen and afford rigidity to the body of the post.

35 8 represents a plug fitting in the upper end of the post, and which is composed of wood or some other non-conductor of electricity.

40 45 This plug is grooved, as shown at 9, Fig. VIII, to receive the inner edges of the narrow strips 10, preferably of metal, placed between the flanges 4 above the diaphragm 6. (See Figs. IV and VIII.) The flanges 4 do not extend 50 above the point indicated at 11, Fig. IV, but

the body of the members 2 3 extend to a point indicated at 12, Fig. IV.

13 represents the hub of arms 14, carrying the wire-supports 15 of an electric-light or other system. The hub 13 fits over the portion of the members 2 3 of the post between the points indicated at 11 and 12, and to prevent the arms from turning, the lower end of the hub 13 is notched to receive the upper ends of the flanges 4, as shown in Fig. IV and 60 by dotted lines in Fig. IX—that is, the lower end of the hub 13 is notched to fit down over the upper ends of the flanges 4, and thus the hub 13, with the arms 14, is prevented from turning around on the post. 65

16 represents a cap fitting over the plug 8 and held thereto by screws 17, and this cap is provided with a flange 18, fitting over the upper end of the hub 13.

19 represents a rod or spindle fitting in a 70 central socket of the plug 8 and held from turning therein by means of a pin 21, passing through the spindle (see Figs. IV and V) and through a perforation in the plug 8. The spindle 19 may have two perforations to 75 receive the pin 21, as shown in Fig. V, or more, if desired, so that the spindle may be turned and held to an adjustment of less than one revolution of it. The upper end of the spindle 19 is provided with a non-circular 80 head 22, by which it may be turned by removing the cap 16 and pin 21, and after it is turned the pin and cap would be reapplied.

On the lower end of the spindle 19 is coiled the inner end of the guy-wire 23, that supports 85 the trolley-wire of an electric system. This wire passes through a guide-plug 24, of non-conducting material, which fits in a slot 25 in the post, as shown in Figs. IV, VI, and VII, said plug having notches or grooves 26 in the 90 sides, which receives the edges of pole, as shown in Fig. VI. It will thus be seen that the guy-wire is insulated from the metallic post, and that by adjusting the rod or spindle 19 the wire may be tightened. Above the 95 guy-wire 23 the post is provided with a block 30, preferably composed of some insulating material, and which is held to the flange upon the pole by means of straps 31. To this block is secured the guard-wire 32, (see Fig. I,) 100

which prevents electric and other wires from falling onto the trolley-wire.

In Fig. X, I have shown a modification, where the insulator 8, instead of being a plug, is in the form of a sleeve and fits over the upper end of the pole, and the cap is provided with sockets 30 to receive wire-supporting arms.

I claim as my invention—

- 10 1. A metallic pole having a plug 8 of non-conducting material, in combination with a shaft or spindle 19 for holding a wire, substantially as and for the purpose set forth.
- 15 2. A metallic pole having a plug 8, in combination with an adjustable shaft or spindle 19 for holding a wire, substantially as and for the purpose set forth.
- 20 3. A metallic pole having a plug 8 for receiving an adjustable shaft or spindle 19, adapted to hold a wire, in combination with a pin passing through the plug and shaft or spindle, substantially as and for the purpose set forth.
- 25 4. A metallic pole having a slot 25, in combination with a plug 23 and a rod or spindle fitted in the upper end of the post and to which a wire passing through the plug is se-

cured, substantially as and for the purpose set forth.

5. A metallic pole having strips 10, a plug 30 grooved to receive said strips and fitting in the upper end of the pole, a shaft or spindle fitting in the plug and adapted to hold a wire, and means for uniting the spindle to the plug, substantially as set forth. 35

6. In a metallic pole, the combination of a plug fitting in the end of the pole, a removable cap fitting on the plug, an adjustable spindle fitting in the plug and adapted to hold a wire, and means for holding the spindle, substantially as and for the purpose set forth. 40

7. In a metallic pole, the combination of the plug 8, arms having a hub fitting over the plug and notched to receive the flanges on 45 the pole, a cap fitting on the plug, a spindle fitting in the plug and adapted to hold the wire, and means for holding the spindle, substantially as and for the purpose set forth.

EDMOND VERSTRAETE.
